CLAIM

The ornamental design for a motor vehicle front lower grille with bars, as shown and described.

DESCRIPTION

FIG. 1 is a left, front perspective view of a motor vehicle front lower grille with bars showing our new design; FIG. 2 is a right, rear perspective view thereof; FIG. 3 is a front elevational view thereof; FIG. 4 is a rear elevational view thereof; FIG. 5 is a right side elevational view thereof; FIG. 6 is a left side elevational view thereof; FIG. 7 is a top plan view thereof; FIG. 8 is a bottom plan view thereof; and, FIG. 9 is another front elevational view thereof, shown mounted on a vehicle.

The vehicle portion shown in broken lines in the FIG. 9 drawing view are for illustrative and environmental purposes that form no part of the claimed design.
